UNITED STATES PATENT OFFICE.

WILLIAM AISENSTEIN, OF CHICAGO, ILLINOIS, ASSIGNOR TO WILMORT MANUFACTURING COMPANY, OF CHICAGO, ILLINOIS, A CORPORATION OF ILLINOIS.

COMBINED ASH-TRAY AND PIPE-CLEANER.

1,356,586.

Specification of Letters Patent. Patented Oct. 26, 1920.

Application filed January 24, 1919. Serial No. 272,818.

To all whom it may concern:

Be it known that I, WILLIAM AISENSTEIN, a citizen of the United States, residing at Chicago, in the county of Cook and State of Illinois, have invented a certain new and useful Improvement in Combined Ash-Trays and Pipe-Cleaners, of which the following is a full, clear, concise, and exact description, reference being had to the accompanying drawings, forming a part of this specification.

My invention relates to improvements in a combined ash tray and pipe cleaner, the object being to provide a convenient device of this character which shall combine a receptacle for the material removed from the pipe and a pin or spike, in convenient position, for use in loosening the grains of tobacco, dottle or ash carried by the pipe.

20 The pipe cleaner of my invention preferably includes a bowl-like receptacle for receiving the tobacco or refuse removed from the pipe and a spike or pin carried by the receptacle and in position so that the pipe bowl can be placed over or upon same and so that the receptacle will receive or catch the loosened material.

25 The device is so arranged that the pipe bowl can be placed upon the spike, which thus loosens or breaks apart the compacted grains of tobacco and ash in the bowl, which will fall out into the receptacle.

The cleaner of my invention is not only a device of great convenience, but it is an article which tends to cleanliness in that a convenient receptacle is provided to catch and retain the discarded grains of tobacco, thus preventing their being scattered about, and it is also an article capable of being produced in many forms and embellished with any desired ornamentation and hence it is capable of being produced in cheap or expensive forms. It is consequently an article of great merit for smokers' use.

45 My invention will be more readily understood by reference to the accompanying

drawing, which is a central vertical section of my improved pipe cleaner.

I have provided a casing 21 which may be made of wood or metal and having a flat bottom 22 and a bowl-like open top 23. I also provide a glass or similar lining or inner vessel 24, which as shown fits snugly within the casting 21, which has its rim flush with the rim of the casing, but which can be readily removed for cleaning same, by the cleaning pin 14 which is fastened to the lining or inner vessel by means of a nut 26 on the lower end of the pin and a shoulder or collar 27 opposed to same.

60 The lining 24 is provided with a raised portion 28 to accommodate the nut 26. The casing 21 may be embellished by feet 13 and a flange 25. As an additional means to break up the dottle I provide the auxiliary pin 15, having a bead 18 and stowed in a hole 16 in the casing 21. The manner in which the pipe is applied to the cleaning pin 14 is shown by the dotted lines P. Since the lining 24 is surrounded by the casing 21 70 it also performs the function of a handle to remove and empty the lining without contact with the refuse.

As it is obvious that many modifications of my invention will readily suggest themselves to one skilled in the art I do not limit or confine my invention to the specific structures herein shown or described, except within the scope of the appended claim.

80 I claim:

A combined ash tray and pipe cleaner comprising an outer bowl, a rigid liner fitting the interior of said bowl and having its rim terminating substantially flush with the rim of the bowl, and a pin secured to 85 said liner and extending upwardly from the bottom thereof and forming a pipe cleaner and a handle whereby said liner may be removed from said bowl.

In witness whereof I hereunto subscribe my name this 18 day of January, A. D. 1919.

WILLIAM AISENSTEIN.
